[57] **CLAIM**

The ornamental design for a bootie for a canine, as shown and described.

DESCRIPTION

FIG. 1 is a perspective view of a bootie for a canine showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is bottom plan view thereof.

The broken line showing of a dog and the second bootie is for illustrative purposes only and forms no part of the claimed design.
